SMELTING FURNACES

Oscar Frederick Swenson, deceased, late of South Pasadena, Calif., by Walter L. Engelhardt, administrator, 653 S. Lake St., Pasadena, Calif.

Filed Feb. 10, 1958, Ser. No. 714,441

6 Claims. (Cl. 263—39)

This invention relates to improvements in smelting furnaces of the type employed to melt pig iron, cast iron scrap, steel scrap, iron or iron ore concentrate briquettes and the like.

The application may be considered as a continuation-in-part of the application on Smelting Furnaces filed August 13, 1956, Serial No. 603,595, now abandoned.

The above-mentioned application discloses a smelting furnace consisting of two smelting chambers arranged in end to end relationship and in communication with each other at their inner ends. At the outer ends of the chambers there are heating means in the form of oil burners and a duct connects the outer ends of the chambers to each other and to a stack. When one chamber is used as a smelting furnace the oil burner in the outer end thereof is utilized. The other chamber is used as a pre-heater, the intention being that the heat derived from the oil burner be utilized to melt the material in the smelting chamber and that the products of combustion pass therefrom into the other chamber and be utilized to pre-heat the material that is disposed therein and which is ultimately to be melted.

After passing through the pre-heating chamber the hot gases discharge into the duct and are carried therethrough to the outer end of the melting chamber, excess gases being released through the stack. When the contents of the melting chamber have been melted and poured the pre-heating chamber is then utilized as a melting chamber and the oil burner in the outer end thereof is then utilized to bring its contents to a molten condition. The chamber that was previously used as a melting chamber is then charged with material and is used as a pre-heating chamber. The direction of flow of hot gases through the two chambers and through the duct is reversed.

The relatively long passage through the chamber that is utilized as a pre-heating chamber and through the return duct causes the hot gases which reenter the melting chamber to be sufficiently cooled that the utilization of the available heat derived from the burner is somewhat limited.

It is an object of the present invention to provide an improved furnace having generally similar characteristics in that there are two melting chambers arranged in end to end relationship and in communication with each other with burners applicable to the outer ends of each chamber. However, instead of causing all of the products of combustion produced in the melting chamber to pass through the pre-heating chamber and then to be returned through a relatively long duct, these hot gases are caused to flow a divided path or paths. A substantial portion of the hot gases developed in the melting chamber are immediately returned to the outer end of the melting chamber through a relatively short return duct so that these hot gases at the time they reenter the melting chamber, are quite hot and can be advantageously used to assist in melting the contents of the melting chamber and contribute to the maintenance of a reducing atmosphere therein. Only a portion of the hot gases discharged

2

from the melting chamber are caused to pass through the pre-heating chamber to preheat the contents thereof, and as there is a great excess of gases generated and discharged through the melting chamber over the amount required to be returned thereto and over the amount required to pass through the pre-heating chamber to preheat its contents, the excess of gases are permitted to pass directly to the stack. With this arrangement, the available heat derived from the burner is most advantageously utilized, contributing to a very efficient furnace that can be used to melt scrap and/or to reduce iron ores.

With the foregoing and other objects in view, which will be made manifest in the following detailed description and specifically pointed out in the appended claims, reference is had to the accompanying drawings for an illustrative embodiment of the invention, wherein:

Figure 1 is a top plan view of the improved smelting furnace embodying the present invention;

Fig. 2 is a vertical section taken substantially upon the line 2—2 upon Fig. 1 in the direction indicated; and

Figs. 3, 4, and 5 are vertical sections taken substantially upon the lines 3—3, 4—4, and 5—5, respectively, in the directions indicated upon Fig. 1.

Referring to the accompanying drawings wherein similar reference characters designate similar parts throughout, the improved furnace consists of two somewhat barrel-shaped chambers 10 and 11 formed of any suitable material and preferably lined with refractory material. These chambers are arranged in alignment and in end to end relationship, and may be regarded as coaxially arranged on opposite sides of a central partition 12 between them. The exteriors of the chambers are equipped with circumferentially extending rails 13 which roll in grooved supporting rollers 14, see Fig. 4, and enable each chamber to be rotatably oscillated and to be tilted independently of each other. As a means for rotatably oscillating the chambers there is illustrated a hydraulic ram 15 connected as at 16 for each chamber, and this hydraulic ram has the fluid supplied to and exhausted from its cylinder by means of an electric valve, not shown.

When end chamber 10 or 11 is being utilized as a melting chamber its ram 15 is caused to reciprocate either continuously or periodically so that the molten contents of the chamber will have its corrosive effect on the refractory lining distributed over the interior surface. When the contents of the chamber is molten it may be poured from the chamber through a pouring spout 17 in which case, the hydraulic ram is actuated beyond the length of stroke required for reciprocation and rotates the chamber into a position wherein the molten contents can be poured from the pouring spout. Charging doors 18 are arranged in the sides of the chambers horizontally opposite the pouring spouts and the chambers are charged with the material that is to be melted therethrough.

At the outer ends of the chambers 10 and 11 there are end walls 19 and 19a in which there are formed passages 20 and 21 that are coaxially arranged with respect to the chambers 10 and 11. The outer ends of these passages may have positioned therein heating means in the form of oil burners 22 and 23 which discharge flame and products of combustion through their respective passages 20 or 21 into their respective chambers 10 or 11. It will be understood, however, that when burner 22 is in position and is being utilized to melt the contents of chamber 10 that chamber 11 is used as a pre-heating chamber, in which case burner 23 is removed and is replaced by a door, not shown. Conversely, if chamber 11 is being used as a melting chamber and chamber 10 is being used as a pre-heating chamber, the oil burner 23

is in applied position and burner 22 is removed and is replaced by a door, not shown.

24 and 25 are hollow water-cooled rings having mutually interfitting portions, rings 24 being mounted on the end walls 19 and 19a, respectively, and on the partition 12. Rings 25 are mounted on their respective chambers 10 and 11 and may be secured to encircling metal rings 26 in any suitable manner. While some clearance may exist between the ends of the chambers 10 and 11 and the end walls 19 and 19a and the partition 12, the interfitting engagement between the water-cooled rings 24 and 25 tends to confine flame and hot gases against escape, even though the chambers oscillate relatively to the stationary end walls and partition.

In the partition 12 there is formed a passage 27 that is coaxially arranged with respect to the chambers and flow through this passage is regulated by a water-cooled gate valve or the equivalent, indicated at 28. Each chamber 10 and 11 has in association therewith a return duct identified by the reference characters 29 and 30, respectively. A portion of each return duct is formed in the central partition 12 and extends through the supporting foundation for the furnace. Each return duct terminates in the end wall 19 and 19a, respectively, and communicates with the passages 20 and 21, respectively, in the manner illustrated in Fig. 3. Each return duct 29 and 30 has in communication therewith a branch exhaust duct, these ducts being indicated at 31 and 32, respectively. Flow through these exhaust ducts is controlled or regulated by water-cooled valves 33 and 34, respectively. These ducts lead to a stack 35 and flow into the stack is regulated by a water-cooled valve 36. Additional exhaust ducts 37 and 38 lead from the passage 27 in the partition 12 on opposite sides of the valve 28 to the stack 35. These ducts are regulated by water-cooled valves 39 and 40, respectively.

The operation and advantages of the improved furnace are substantially as follows:

Assuming that both chambers 10 and 11 have been charged with material to be melted and that chamber 10 is initially the melting chamber, burner 22 is applied to end wall 19 and burner 23 removed and replaced by a door as previously explained. Flame and products of combustion are discharged from burner 22 to bring the contents of chamber 10 up to a molten condition, and during this melting this chamber is continuously or periodically oscillated. Valve 28 is partially opened to permit some of the hot gases to pass from chamber 10 into chamber 11 to pre-heat the charge in chamber 11. Valve 28, however, is not opened entirely so that a substantial portion of the hot gases are returned through the return duct 29 for re-entry in passage 20. These returned hot gases impart heat to the charge in chamber 10 and cooperate with the heat generated by the burner 22 in bringing the charge in chamber 10 up to molten condition. They also contribute to the maintenance of a reducing atmosphere in chamber 10. There is an excess of gases delivered or supplied to passage 27 over and above that required to recirculate and over and above that required to pass through chamber 11 for pre-heating purposes. This excess of hot gases is permitted to pass through the exhaust duct 37 to stack 35, it being understood that valves 39 and 36 are partially opened for this purpose. While the furnace is in this condition valve 33 is closed but valve 34 which controls exhaust duct 32 is partially open. That fraction of the gases which pass into chamber 11 for pre-heating purposes enters the passage 21 and flows from right to left as viewed in Fig. 2 through the exhaust duct 30.

These gases are drawn from the duct 30 into the exhaust duct 32 and into the stack 35 by the updraft induced by the stack, it being understood that valves 34 and 36 are both partially open. When the contents of chamber 10 have been melted and are ready for pouring its hydraulic ram 15 is actuated to tilt chamber 10 into a

position wherein slag can be poured from the spout 17 and then, after the slag has been poured, the molten metal may be poured from the spout. The aperture in the wall of the chamber leading to the spout is normally closed by a temporary fireclay plug in accordance with conventional practice while the contents of chamber 10 are being rendered molten.

When the contents of chamber 10 has been poured the charge in chamber 11 will have reached its fully pre-heated condition or substantially so. Chamber 10 is quickly recharged and burner 22 is removed and replaced by a door. Burner 23 is applied to the outer end of end wall 19a and is ignited. This burner discharges in a reverse direction or from right to left as viewed in Fig. 2, and the heat generated therefrom is utilized to bring the pre-heated charge in chamber 11 to a molten condition. Once that valve 28 has been adjusted it is ordinarily unnecessary to readjust this valve when the furnace is being reversely operated to melt the contents of chamber 11. A portion of the hot gases is returned from the central partition 12 through duct 30 to passage 21 and removal of these gases to the stack is prevented by closing valve 34. Another portion of the hot gases passes the partially open valve 28 through chamber 10 which is now being utilized as a pre-heating chamber to pre-heat the charge therein. These gases on reaching passage 20 flow downwardly and into duct 29 from which they may pass to the stack through exhaust duct 31. In this position of operation valve 33 is partially open, permitting flow to the stack through the exhaust duct. Valve 39 is closed and valve 40 partially opened to permit flow of excess of hot gases from passage 27 directly to the stack 35.

The improved furnace may be advantageously used to produce steel directly from iron ore, or it may be utilized advantageously where the charge is composed partially of iron ore and partially of scrap. It may also be used for melting the metallic contents of various other ores.

As the return ducts 29 and 30, respectively, are relatively short and serve to return quickly a substantial fraction of the hot gases developed by the burners to the outer ends of their respective chambers, the heat available in these hot gases is most advantageously utilized. These gases being rather rich in carbon monoxide tend to contribute to the maintenance of a reducing atmosphere in the chambers which is essential to reduction oxides. As there is a large excess of hot gases a portion of these gases is transmitted to the other chamber for the purpose of pre-heating the contents thereof and the excess of hot gases is allowed to escape to the stack directly. The valves are strategically located to enable proper adjustment to meet various conditions.

Various changes may be made in the details of construction without departing from the spirit and scope of the invention as defined by the appended claims.

I claim:

1. A smelting furnace comprising means providing two smelting chambers arranged in end to end relation each of which is oscillatable independently of the other, heating means for each chamber located adjacent the outer end thereof, means for returning a portion of the hot gases generated by the heating means from adjacent the inner end of each chamber to the outer end thereof for recirculating through the chamber, means adjacent the inner ends of the chambers for conducting a portion of the gases from the chamber being heated through the other chamber to preheat the contents thereof, a stack, and means for optionally connecting the stack to the returning means of each chamber.

2. A smelting furnace comprising means providing two smelting chambers arranged in end to end relation each of which is oscillatable independently of the other, heating means for each chamber arranged to discharge therein from adjacent its outer end, a recirculating duct for each chamber communicating with the inner end

thereof and the outer end thereof, a stack, exhaust ducts connecting the recirculating products to the stack, and means for controlling the flow of gases from the recirculating ducts through the exhaust ducts to the stack.

3. A smelting furnace comprising means providing two smelting chambers arranged in end to end relation each of which is oscillatable independently of the other, heating means for each chamber arranged to discharge therein from adjacent its outer end, a recirculating duct for each chamber communicating with the inner end thereof and the outer end thereof, a stack, exhaust ducts connecting to the recirculating products to the stack, means for controlling the flow of gases from the recirculating ducts through the exhaust ducts to the stack, and additional exhaust ducts communicating with the inner ends of the chamber and with the stack, and means for controlling the flow of gases through said additional exhaust ducts.

4. A smelting furnace comprising means providing two smelting chambers arranged in coaxial alignment each of which is oscillatable independently of the other, means for heating each chamber from adjacent the outer end thereof, return ducts communicating with the inner ends of said chambers for returning portions of the hot gases from each chamber to the outer end thereof, means for regulating the flow from the inner end of one chamber into the inner end of the other, a stack, exhaust ducts connecting the recirculating ducts to the stack, and means for regulating the flow through said exhaust ducts.

5. A smelting furnace comprising means providing two smelting chambers arranged in coaxial alignment

each of which is oscillatable independently of the other, means for heating each chamber from adjacent the outer end thereof, return ducts communicating with the inner ends of said chambers for returning portions of the hot gases from each chamber to the outer end thereof, means for regulating the flow from the inner end of one chamber into the inner end of the other, a stack, exhaust ducts connecting the recirculating ducts to the stack, means for regulating the flow through said exhaust ducts, and additional exhaust ducts connecting the inner ends of the chambers to the stack, and means for regulating the flow through said additional exhaust ducts.

6. A smelting furnace comprising means providing two smelting chambers arranged in coaxial alignment each of which is oscillatable independently of the other, means for heating each chamber adjacent its outer end, return ducts communicating with the inner ends of said chambers for returning portions of the hot gases from each chamber to the outer end thereof, means between the return ducts for permitting but regulating flow from the inner end of one chamber into the inner end of the other chamber whereby a portion of the hot gases generated in either chamber will be returned to the outer end thereof, and the remainder of such hot gases will be permitted to pass into the other chamber to pre-heat the contents thereof.
